UNITED STATES PATENT OFFICE.

GARTH G. GILPIN, OF RIVERSIDE, ILLINOIS, ASSIGNOR TO WALTER P. MURPHY, OF NEW YORK, N. Y.

METAL FRAMING OR END REINFORCEMENT FOR RAILWAY CARS.

Application filed December 26, 1919. Serial No. 347,373.

To all whom it may concern:

Be it known that I, GARTH G. GILPIN, a citizen of the United States, residing at Riverside, in the county of Cook and State 5 of Illinois, have invented certain new and useful Improvements in Metal Framing or End Reinforcement for Railway Cars, of which the following is a specification.

My invention relates to the construction 10 or repair of railway cars, especially box freight cars, and a primary object of the invention is to provide a reenforcement or framing for the end wall of a car of wood construction consisting of a metal structure 15 composed of a single integral casting or of castings and rolled sections rigidly united together, the members of which structure are so formed and disposed as to give maximum strength and rigidity to the 20 end wall of the car both as against cargo thrusts and also against weaving, or like strains, with a minimum weight of metal. The invention may be employed either in the 25 repair of old cars or in new equipment and is applicable, with certain constructional modifications, either to single sheathed or double sheathed cars.

The invention is illustrated, in certain preferred embodiments, in the accompanying drawings, in which—

Fig. 1 is an end elevation of the superstructure of a railway box car of the single sheathed type provided with the framing or reenforcement of my invention.

Figure 2 is a sectional plan on line 2—2 of Fig. 1.

Fig. 3 is a vertical sectional view on line 3—3 of Fig. 1.

Fig. 4 is a view similar to Fig. 3, illustrating a modified construction in which the structural elements of the framing are separately formed and bolted or riveted together, the intermediate upright members consisting of Z-bars.

Fig. 5 is an end elevation illustrating this modified construction.

Fig. 6 is a sectional plan on line 6—6 of Fig. 5.

Fig. 7 is a view, similar to Fig. 6, illustrating a further modification in which I-beams are used in place of the Z-bars shown in Figs. 4, 5 and 6.

Fig. 8 is an end elevation of a framing or reenforcement intended particularly for double sheathed box cars and illustrated in 55 that connection.

Fig. 9 is a plan view, partly in section, on line 9—9 of Fig. 8, showing further details of this construction.

Fig. 10 is a vertical sectional view on line 60 10—10 of Fig. 8.

Fig. 11 is a fragmentary elevation of a modification of the construction shown in Figs. 8, 9 and 10.

Fig. 12 is a fragmentary sectional plan 65 on line 12—12 of Fig. 11, and

Fig. 13 is a detail sectional view on line 13—13 of Fig. 11.

Like characters of reference designate like parts in the several figures of the drawings. 70

Referring first to Figs. 1, 2 and 3, 25 designates the end sheathing boards of a single sheathed car, 26 the side sheathing boards, 27 the flooring and 28 the draft sills, which are shown as connected at their extremities 75 to a striking casting 29 and united together by a cover plate 30.

The end framing employed in this construction consists of a single cast structure comprising an upper transverse member 31 80 which constitutes, in effect, the end plate of the car and is provided preferably with an inturned rigidifying flange 32 which supports the roof structure 34 of the car, a lower transverse member 35 which with an angle 85 bar 36 constitutes, in effect, the end sill of the car, an intermediate transverse member 37, upright side or corner members 38, 38 and intermediate members 39, 39. The lower transverse member 35 is preferably formed 90

with downwardly projecting extensions 40 formed with push pole pockets 41. The upright side members 38 are formed with flanges 42 which overlap the side sheathing boards 26 which are secured thereto. The intermediate upright members 39 are preferably channel-shaped in cross section and project out beyond the plane of the upright side members, the channel's being of uniform depth or thickness from the floor to points 100

approximately half way between the floor and roof and tapering in depth or thickness from there on toward their upper extremities. The intermediate transverse member

37 is also preferably channel-shaped in cross section and extends out beyond the plane of the upright side members with its extremities tapering in depth toward said side members. In order to strengthen the structure fillets 43 are provided at the intersections of upright members 38 and 39 with the transverse member 37.

The channels of the intermediate upright members 39 (the same is true of the channel transverse member 37) are open toward the car and in these channels are arranged wooden filler strips 44 secured in place by bolts 45. The wooden members 44 provide nail strips for the end sheathing boards 25. The end angle bar 36 is suitably secured to the lower transverse member 35 of the framing and also to the striking casting 29, a metal filling strip 46 being interposed between the horizontal leg of the angle and the striking casting.

The framing structure shown in Figs. 4, 5 and 6 instead of being composed of a single integral casting is made up of separately formed members, some of which are commercial rolled sections, suitably riveted or bolted together. The structure comprises an upper transverse member 47 preferably a casting and formed with an inturned flange 48 for supporting the roof of the car, a lower transverse member 49, also a casting, preferably, having an inturned flange 50 secured to the striking casting 29 and other portions of the under frame, upright side members 51, 51, which are angle bars, and upright intermediate members 52 are Z-shaped in cross section. The lower transverse member 49 is formed at its extremities with enlargements 53 for the push pole pockets 54 and to provide extended bearings for the lower ends of the angle bar side members 51 which are secured thereto by rivets 55, the angle bars 51 preferably extending down to the lower corners of these enlargements. The upper transverse member 47 is provided with similar wings or enlargements 56 to which the upper ends of the angle bars 51 are secured. The intermediate members 52 are riveted, through their outstanding webs 57, to angular brackets 58 formed on the transverse members. The outstanding flanges of the brackets 58 are extended out over the faces of the transverse members 47, 49 as shown at 59 in order to strengthen the connections between the transverse members and the upright Z-bars 52, these connections being further strengthened preferably by diagonally disposed flanges 60.

In Fig. 7 I have shown a construction in which I-beams 61 are employed in place of the Z-bars 52. The transverse members at the top and bottom of the car, the lower member 62 alone being shown, being slotted for reception of the upstanding webs of the I-beams and formed with angularly disposed

brackets 63 arranged in pairs on opposite sides of the slots, the outstanding webs of the I-beams being secured to these brackets by rivets 64.

In Figs. 8, 9 and 10 I have shown an integral cast reenforcement for the end wall of a double sheathed box car of wood construction. The end structure of the car as here shown, comprises an end plate 65, an end sill 66, sheathing boards 67, lining boards 68, corner posts 69, intermediate posts 70, side sills 71 and side plates 72.

The end reenforcement comprises an upper transverse member 73, a lower transverse member 74, upright side members 75, 75 and 80 upright intermediate members 76, 76 which are preferably in line with the intermediate wooden end posts 70, 70. The side members 75 are formed with flanges 77 which overlap the side walls of the car and are extended to form wings 78 and 79 at their upper and lower ends, these wings being secured to the side plates 72 and the side sills 71, respectively. Additional enlargements or wings 80 are provided for engagement with the side belt rails 81 of the car. The lower transverse member 74 is formed preferably with an inturned flange 82 which extends under the end sill 66 and is widened at its extremities to underlie the ends of the side sills as shown at 83. The striking casting 84 is preferably formed integrally with the lower transverse member 74 although it might be made separately therefrom if desired. The upper transverse member 73 is formed with an outstanding and down turned web 85 which is preferably deepest at the middle of the car and tapers in depth toward the sides of the car. At the junction of the side members 75 with the upper transverse member 73 strengthening ribs 86 are provided which extend around the corners of the car. The intermediate upright members 76 are in the form of I-beams as shown particularly at the right hand side of Fig. 8. These I-beam structures taper down and die out upon the lower transverse member 74 as shown at 87 in Fig. 10. The outer flanges 88 thereof are continuous with the outstanding web 85 of the upper transverse member 73. I have shown the brake staff 89 as extending through a perforation in web 85. In order to fasten the wooden intermediate posts 70 to the upright members 76 of the end reenforcement the outstanding webs 90 of the intermediate upright members are formed at intervals with bosses 91 perforated to receive bolts 92 which pass through the bosses and through posts 70.

The construction shown in Figs. 11, 12 and 13 is substantially the same as that shown in Figs. 8, 9 and 10 except that the reenforcing structure of Figs. 11 and 12 is provided with an intermediate transverse reinforcement 93 which is aligned with the

end belt rail 94 and like the upright intermediate members 95 is I-shaped in cross section. The transverse intermediate member 93 tapers in depth or thickness at each end 5 from the upright intermediate member to the side member 96. The rest of the structure may be like that shown in Figs. 8, 9 and 10.

I claim:

- 10 1. A metal reenforcement or framing adapted to be fitted over the end wall of a railway box car comprising cast transverse members at the roof and floor of the car, upright members at the sides of the car provided with flanges which overlap and are attached to the side walls thereof, and upright members extending from one transverse member to the other intermediate the sides of the car, all united to form a unitary structure.
- 15 2. A metal reenforcement or framing for the end wall of a railway box car comprising cast transverse members at the roof and floor of the car, upright members at the sides of the car provided with flanges overlapping the side walls thereof, and upright members extending from one transverse member to the other intermediate the sides of the car the lower portions of which are of greatest cross-sectional area and the upper portions of which diminish in cross-sectional area toward their upper extremities.
- 20 3. A metal reenforcement or framing adapted to be fitted over the end wall of a railway box car comprising cast transverse members at the roof and floor of the car, upright members at the sides of the car provided with flanges overlapping the side walls thereof, and upright members extending from one transverse member to the other intermediate the sides of the car which are angular in their cross section and project out beyond the plane of said upright side members.
- 25 4. A metal reenforcement or framing adapted to be fitted over the end wall of a railway box car comprising transverse members at the roof and floor of the car, upright members at the sides of the car provided with flanges overlapping the side walls thereof, and upright members extending from one transverse member to the other intermediate the sides of the car, said structure consisting of a single integral casting.
- 30 5. A metal reenforcement or framing for the end wall of a railway box car comprising transverse members at the roof and floor of the car, upright members at the sides of the car provided with flanges overlapping the side walls thereof, upright members extending from one transverse member to the other intermediate the sides of the car, and a transverse member intermediate the upper and lower transverse members extending 60 from side to side of the car and tapering

from a point adjacent the vertical center line of the end to its extremities, said structure consisting of a single integral casting.

6. A metal reenforcement or framing adapted to be fitted over the end wall of a railway box car comprising transverse members at the roof and floor of the car, upright angular side members integral with the transverse members, and upright members integral with and extending from one transverse member to the other intermediate the side members and projecting out beyond the same.

7. A metal reenforcement or framing for the end wall of a railway box car comprising transverse members at the roof and floor of the car, upright angular side members integral with the transverse members, and upright members integral with and extending from one transverse member to the other intermediate the side members and projecting out beyond the same, said intermediate upright members being of greater cross sectional area adjacent the horizontal center line of the end than at their upper extremities.

8. A metal reenforcement or framing adapted to be fitted over the end wall of a railway box car comprising transverse members at the roof and floor of the car, upright angular side members integral with the transverse members, upright members integral with and extending from one transverse member to the other intermediate the side members, and an intermediate transverse member integral with said side and intermediate upright members.

9. A metal reenforcement or framing for the end wall of a railway box car comprising transverse members at the roof and floor of the car, upright angular side members integral with the transverse members, upright members integral with and extending from one transverse member to the other intermediate the side members, and an intermediate transverse member integral with said side and intermediate upright members, said intermediate upright and transverse members projecting beyond the plane of the upper, lower and side members.

10. A metal reenforcement or framing for the end wall of a railway box car comprising transverse members at the roof and floor of the car, upright angular side members integral with the transverse members, upright members the upper ends of which taper in thickness toward the roof and which are integral with and extend from one transverse member to the other intermediate the side members, and an intermediate transverse member integral with said side and intermediate upright members, said intermediate transverse members projecting beyond the plane of the upper, lower and side members, and being of greater thick- 130

ness longitudinally of the car at their middles and tapering in thickness toward their extremities.

11. In a single sheathed box car, a metal reinforcement or framing comprising an upper transverse member providing a roof support, a lower transverse member providing an end sill, upright intermediate members formed with channels open on the side 10 toward the car, and filler strips in said channels to which the sheathing boards of the end may be secured.

12. In a single sheathed box car, a metal reinforcement or framing comprising an upper transverse member providing a support for the roof structure, a lower transverse member providing an end sill, upright intermediate members and a transverse intermediate member formed with 20 channels open on the side toward the car, and filler strips in certain of said channels to which the sheathing boards of the car end may be secured.

13. In a single sheathed box car, a metal reinforcement or framing adapted to fit over the end wall of the car comprising an upper transverse member, a lower transverse member, upright intermediate members, and a 25

transverse intermediate member, said intermediate members being channel-shaped in 30 cross section.

14. In combination with the side walls and end sheathing of a railway box car of the single sheathed type, of an end reinforcement or framing consisting of a single 35 integral casting comprising upper and lower transverse members, the latter formed with downwardly projecting push pocket extensions, upright side members angular in cross section, intermediate upright members channel-shaped in cross section, 40 and an intermediate transverse member channel-shaped in cross section.

15. In combination with a wooden end wall structure of a railway box car, of a 45 metal end reinforcement or framing consisting of a single integral casting comprising an upper transverse member formed with a rigidifying web, a lower transverse member, angular side members adapted to 50 overlap the side walls of the car and be secured to the frame members of the car, and intermediate upright members extending from one transverse member to the other.

GARTH G. GILPIN.
